UNITED STATES PATENT OFFICE.

RICHARD LANE, OF BOSTON, MASSACHUSETTS.

AWNIN.

SPECIFICATION forming part of Letters Patent No. 764,245, dated July 5, 1904.

Application filed January 28, 1904. Serial No. 190,939. (No model.)

To all whom it may concern:

Be it known that I, RICHARD LANE, a citizen of the United States, residing at Boston, in the county of Suffolk and State of Massachusetts, have invented an Improvement in Awnings, of which the following description, in connection with the accompanying drawings, is a specification, like numerals on the drawings representing like parts.

This invention relates to an awning and comprises a novel means for supporting the awning and vertical operating-shaft therefor and also a novel means for locking the awning in any adjusted position.

The features wherein my invention resides will be more fully hereinafter described and then pointed out in the claims.

In the drawings, Figure 1 is an elevation of my improved awning. Fig. 2 is a section 20 on the line $x-x$, Fig. 1. Fig. 3 is a section through the casing inclosing the crank member on the line x , Fig. 1. Fig. 4 is a detail of the bracket. Fig. 5 is a section on line $y-y$, Fig. 2.

3 designates the awning proper, which is rolled upon a suitable roller 4. The lower edge of the awning is connected to the usual braces 5, which are pivoted to the side of the building, as at 6. One end of the roller 4 is 30 supported in any suitable bracket 7, secured to the side of the building. The other end of said roller has rigid therewith a bevel-gear 8 and is supported by a bearing member 9, which in turn is supported by a suitable bracket 10, rigidly secured to the wall. Any suitable connection between the bearing member and roller may be employed, and, as herein shown, said bearing member has the journal 11 projecting therefrom and entering a 35 recess in the end of the roller, as seen in Fig. 5. To prevent the roller 10 from being withdrawn from the pintle 11, I have made the gear-wheel 8 with the hub 68, which enters the recess in the end of said roller and through 40 which the pintle 11 extends, and have fixed to the projecting end of said pintle a collar 69.

In assembling the parts the gear 8 is first slipped over the pintle and the collar 69 applied. Thereafter the gear-hub and pintle are

inserted in the recess in the roller and said gear made fast to said roller.

The bearing member 9 has also projecting therefrom a pin or arm 12, which rests in one of a plurality of notches 13 in the bracket 10. In this form of my invention the projection 55 or pin 12 is in the form of a screw secured to the bearing member; but such construction is not essential. Said bearing member besides supporting one end of the roller 4 also acts as a bearing for the upper end of the vertical actuating-shaft 14, said member being bored vertically to receive the end of the shaft, as shown in Fig. 2. Mounted on said shaft to rotate therewith is a bevel-gear 16, which meshes with and drives the bevel-gear 8 on 60 the roller. This gear 16 is confined within the yoke portion 17 of the bearing member and rests upon the shoulder or bearing 18 thereof. The portion of the shaft which extends through the gear 16 is preferably flat-sided, so that the gear will rotate with the shaft. The object in supporting the gear 16 by the bearing member instead of by the shaft is to prevent said gear from becoming drawn out of mesh with the gear 8 in case the shaft 14 65 gets moved endwise.

Projecting upwardly from the bearing member 9 is an arm 21, having a laterally-projecting portion 22, and depending from the laterally-projecting portion is a second 80 arm 23. The bracket 10 is received between the arms 21 and 23, as seen in Fig. 5. The arms 21 22 23 constitute a safety device, for if the pin 12 becomes broken in any way said arms by dropping onto the bracket prevent 85 the awning from falling. If desired, a locking-screw 25 in the flange 22 may be used to prevent the bolt 12 from turning.

The bracket 10 is preferably made in two parts, one, the base portion, having the 90 notches 13 therein, and the other, the guard portion 27, which closes the upper end of the notches. One end of this guard portion centers in a socket 28 in the bracket, and the other end has an eye 29, which fits over a 95 screw-threaded projection 30 on the base portion.

The mechanism for operating the actuat-

ing-shaft 14 is shown in Figs. 2 and 3. The lower end of said shaft rests in a step-bearing 31 in a stand 44, supported in a suitable casing 32, which is secured to the wall. Fast 5 on said shaft 14 is a bevel-gear 33, which meshes with a driving bevel-gear 34, constituting part of a crank member. Said bevel-gear 34 is carried by a shaft 35, which extends through and is journaled in the casing 10 32 and in the stand 44 and has a head 36 thereon outside of the casing, said head being slotted transversely for the reception of one end of a detachable crank 37. The head is provided with two locking-notches 38, and the 15 crank has a spring-catch 39 thereon adapted to engage one or the other of the notches, as shown in Fig. 2. The object in providing two notches 38 is to permit the crank to be inserted from either direction.

20 Another feature of my invention relates to the manner in which the crank member is locked against rotation when the crank is removed. The crank 37, as above stated, is detachable and is intended to be removed after 25 the awning has been adjusted. The lock I have herein illustrated comprises a pivoted member 39', which is adapted to engage one of a plurality of peripheral notches 40 in a disk 41, rigid with the gear 34, as seen in 30 Fig. 3. As herein illustrated, the member 39' is forked at its ends, where it is pivoted to the stand 44, and its nose portion extends through the stand, the latter being cored out for this purpose, and engages the notches in the 35 disk 41.

45 designates a releasing-pin mounted to slide axially of the shaft 35 and adapted at one end to engage the cam-surface 46 on the locking member, and thereby disengage said member from the disk. The pin projects through 40 the casing, and the end thereof extends partially into the slot in the head 36 and in the path of the crank when the latter is inserted. The end of the crank is beveled, as at 47, so 45 that when it is inserted in the slot it engages the pin 45, forces the same to the right, Figs. 2 and 3, and thereby releases the locking member from the disk 41. This operation is accomplished by the application of the crank 50 to the crank member, and therefore when the crank has been properly applied the device is unlocked and ready for use. Upon the removal of the crank after the awning has been adjusted the locking member will drop 55 by gravity to its locking or operative position, and thereby automatically lock the awning in such position. If desired, a suitable spring 48 may be employed to assist the returning of the lock to operative position.

60 It will be noticed that the releasing member 45 does not extend entirely through the head, but only into the slot, and is therefore protected from manipulation by unauthorized persons. The only way in which the

awning can be unlocked is by the insertion 65 of the crank 37, and as this will always be in the possession of persons authorized to operate the awning it will be impossible for unauthorized persons to tamper with it.

I have also provided means for limiting the 70 opening movement of the awning. As herein illustrated, this comprises a fixed non-rotative collar or nut 50, having a screw-threaded connection with the shaft 14 and received in an extension 51 of the bearing member, and a 75 collar 62, fast on the shaft 14. Said nut has a pin 52 extending therefrom, which plays in a slot 53 in said extension, whereby said nut is held from turning. As the shaft 14 is turned to lower the awning the nut 50 will 80 travel down, and when it engages the portion 54 of the extension 51 the collar 62 will be forced against said extension and the shaft locked from further turning movement.

The crank 37 is made thin and flat, as will 85 be seen, this construction permitting me to use a comparatively flat head 36 and one without any projections, which are liable to be in the way.

While I have described one form which my 90 invention may take, I do not wish to be limited to the details illustrated and described, as these may be varied in many ways without departing from the invention.

Having described my invention, what I 95 claim as new, and desire to secure by Letters Patent, is—

1. In an awning, a roller having a gear rigid therewith, a bearing member by which said roller is supported, a bracket adjustably supporting said bearing member, an actuating-shaft having one end journaled in said bearing member, and a gear operated by said shaft and supported by the bearing member, said gear meshing with the gear on the roller. 100

2. In an awning, a roller, a bearing member by which said roller is supported, a bracket adapted to be rigidly secured to the building and adjustably supporting the bearing member, and an operating-shaft journaled in the 110 bearing member and geared to the roller.

3. In an awning, a roller, a bearing member by which the roller is supported, a fixed bracket having a plurality of notches in any one of which the bearing member may be supported, and an operating-shaft journaled in the 115 bearing member and geared to the roller.

4. In an awning, a roller, a bearing member by which the roller is supported and having a supporting-pin, a fixed bracket comprising a body member provided with a plurality of notches for receiving said pin and a removable guard member to cover the notches, and an operating-shaft journaled in the bearing member and geared to the roller. 120

5. In an awning, a roller, a bearing member supporting said roller, an operating-shaft journaled at one end in said bearing member, 125

a non-rotatable nut having a screw-threaded engagement with said shaft, said nut being held from turning by the bearing member and adapted by its engagement with said member 5 to limit the rotation of the shaft.

6. In an awning, a roller, a vertical shaft geared thereto, a crank member geared to said shaft, said crank member having a transversely-slotted head, a detachable crank adapted to be inserted in said slot, and a lock for the crank member and a lock-releaser normally projecting into the slot whereby it is actuated by the insertion of the crank into said slot.

15 7. In an awning, an actuating-shaft, a crank member geared to said shaft, a casing inclosing said gears, a lock for the crank member inclosed by the casing, a crank detachably secured to the crank member, a lock-releaser 20 adapted to be actuated by the application of the crank to the crank member, and a guard to protect said lock-releaser.

8. In an awning, an actuating-shaft, a crank

member geared to the shaft, said crank member having a transverse slot, a lock for said member, a detachable crank adapted to be inserted in the slot, and a lock-releasing member normally projecting into the slot and in the path of the crank, whereby when the crank is inserted in the slot the lock-releasing member is actuated to release the lock.

9. In an awning, an actuating-shaft, a crank member geared to said shaft, a lock for the crank member, a crank detachably secured to said crank member, a pin to release the lock 35 and constructed to be operated by the application of the crank to the crank member, and a guard extending across the end of the pin.

In testimony whereof I have signed my name to this specification in the presence of two subscribing witnesses.

RICHARD LANE.
